UNITED STATES PATENT OFFICE.

HAROLD G. BAXTER, OF BALDWIN, NEW YORK, AND HUBERT K. KRANTZ, OF WILKINSBURG, PENNSYLVANIA, ASSIGNEES TO WESTINGHOUSE ELECTRIC AND MANUFACTURING COMPANY, A CORPORATION OF PENNSYLVANIA.

SWITCH MECHANISM.

Application filed April 25, 1921. Serial No. 464,168.

Our invention relates to switch mechanism and particularly to switch mechanism of the safety enclosed type.

One object of our invention is to provide a switch box wherein a switch and fuse mechanism is enclosed therein and wherein the box is provided with a hinged cover having an opening through which the fuse elements are accessible and which is closed by a door.

Another object of our invention is to provide a switch box, having the above characteristics, wherein the cover is held latched in closed position so long as the switch is in closed position and wherein the door is so interlocked with the switch that the latter cannot be closed so long as the door is in open position or the switch closed until the door is substantially in fully closed position.

Another object of our invention is to provide a switch box of the above described character wherein the interlocking mechanism for the switch and the covers is of simple and durable construction and which may be readily manufactured and assembled.

These and other objects, that will be made apparent throughout the further description of the invention, are attained by means of the switch mechanism hereinafter described, and illustrated in the accompanying drawings, wherein:

Figure 1 is a front view of the switch mechanism;

Fig. 2 is a section through the housing of the switch mechanism taken on the line II-II of Fig. 1 and showing the switch mechanism in side elevation; and

Fig. 3 is a sectional view through the housing taken on the line III-III of Fig. 1 and showing the switch mechanism in end elevation.

Referring to the drawings, the apparatus includes a housing comprising a bottom wall 4, end walls 5, and side walls 6. The housing is provided with a sheet metal cover 7 that is hinged to one side of the housing by means of the hinges 8. An opening 9 is provided in the cover 7 which is closed by a door 11 that is hinged to the cover by means of the hinges 12.

The switch and fuse mechanism comprises an insulating base or panel 13 that is secured to the bottom of the housing and which is

provided with three sets of pivot jaw members 14 to which are pivoted the switch blade members 15. The switch jaw members 16 are disposed opposite the pivot jaw members and are adapted to receive the free ends of the switch blade members 15.

The switch blade members are operated by an operating bar 17 that is pivoted to the sides 6 of the housing and is connected with the switch blade members 15 through the medium of an insulating bar 18 which is attached to the switch blade members. The bar 18 is provided with a pair of brackets 19 which are engaged by the operating bar 17 in such a manner that the switch blade members may be moved to open or to closed position thereby.

Fuse clip members 21 are mounted upon the panel 13 for the purpose of receiving cartridge fuses 22 and the fuse clips 21 that are adjacent to the pivot jaw members 14 are connected thereto by means of conductors 23. The line terminals (not shown) are adapted to be connected to the switch jaw members 16 and the load terminals (not shown) are adapted to be connected to the fuse clip members 21. It will be apparent from the foregoing that, when the switch is in open position, the fuse clip members 21 are disconnected from the circuit and the fuses may be removed or replaced without injury to the operator.

The fuse clip members are disposed directly beneath the opening 9 in the cover 7 and are accessible therethrough. It is an object of this invention to so interlock the door 11 that the door cannot be opened so long as the switch is in closed position. It is another object to prevent closing movement of the switch so long as the door is open or so long as it occupies any position other than the fully closed position.

With these and other objects in view, the operating bar 17 is provided with a locking plate 24 which is attached thereto by means of the screws 25 and 26. This plate is of irregular shape and is provided with notches 27 and 28, the purpose of which will herein-after appear.

The door is provided with a latch bar 29 which is mounted in guide members 30 that are secured to the underside of the door and in which the latch bar 29 may be reciprocated.

One end of the latch bar 29, when in latched or closed position, projects beneath the cover 7 adjacent the edge of the opening 9 therein and serves to hold the door in closed position. The other end of the latch bar is pivoted at 31 to a locking lever 32 that is pivoted at 33 to the underside of the door 11. This lever is provided, at its free end, with an inwardly extending projection 34 that normally lies at one side of the locking plate 24 and serves to prevent unlatching movement of the latch bar 29 so long as the end 35 of the locking plate 24 lies across its path, as indicated in Fig. 2, wherein the switch is shown in closed position.

When the switch is in open position, the locking plate occupies the position indicated in dotted lines in Fig. 2 and the locking lever 32 may then be so moved as to permit unlatching movement of the latch bar 29. A helical spring 36, which is attached at one end to the underside of the door 11 at 37, is attached at the other end to the locking lever 32 at 38, and serves to normally retain the latch bar 29 in closed position.

It will be apparent from the foregoing that the door cannot be opened so long as the switch is in closed position, as shown in Fig. 2, and that, when the locking plate 24 has been moved out of the path of the projection 34 by reason of the opening movement of the switch, the door 11 may be unlatched and moved to open position.

The locking plate 24 is so designed that it prevents opening movement of the latching bar 29 until the switch is substantially in fully open position wherein the notch 28 registers with the projection 34. Therefore, unless the switch is in fully open position, the door 11 cannot be unlatched.

In order to prevent closing movement of the switch so long as the door 11 is open or except when the door is in fully closed position, the door 11 is provided with a disc 39 having its peripheral edge curved concentric to the hinge of the door. The disc is provided with an extension 41 that projects inwardly through a slot 42 provided in the cover 7. When the switch is in open position, the end 43 of the locking plate 24 clears the projection 41 of the disc and permits opening movement of the door. When the door has been moved toward open position a slight degree, the projection 41 crosses the path of movement of the end 43 of the locking plate 24 and prevents closing movement of the switch. By reason of this arrangement, the switch is held in fully open position so long as the door occupies any position other than the fully open position at which time the extension 41 occupies the position indicated in Fig. 3 wherein closing movement of the locking plate 24 is permitted. It will be apparent from the foregoing that the door 11 must be fully closed

before closing movement of the switch is permitted.

The cover 7 is retained in closed position by means of a latch 44 that is riveted to the side of the housing and which projects through a slot 45 provided therein. This latch is provided with an integral tongue 46 that snaps over the edge of the slot 45 and normally retains the cover 7 in closed position. The latch 44 is provided with a perforation 47 through which the hasp of a padlock may be inserted when it is desired to lock the cover 7 in closed position.

The operating bar may be actuated by any desired form of handle, such as, for instance, an operating handle 48 having a quick-make-and-break mechanism that is enclosed in a housing 49 that is attached to the exterior of the housing. The operating mechanism for the operating bar 17 forms no part of this particular invention and is, therefore, not described in detail.

A bracket 51, which is secured to the side of the housing, as indicated in Figs. 1 and 3, is provided with a series of perforations 52 through which the hasp of a padlock may be inserted after it has been looped around the handle 48 in such manner that it prevents closing movement of the switch. By reason of the arrangement whereby the cover 7 is locked in closed position by means of a key-actuated lock, only authorized persons may open the cover. The cover may be opened independently of the switch interlock and the switch may therefore be inspected while in open or closed position.

It will be apparent from the foregoing that the construction is simple and the locking mechanism is positive in its action and that access may not be had to the fuses unless the switch is in open position.

While we have described and illustrated but one embodiment of our invention, it will be apparent to those skilled in the art, that various changes, modifications, substitutions, additions and omissions may be made in the apparatus illustrated without departing from the spirit and scope of the invention, as set forth in the appended claims.

We claim as our invention:

1. Switch mechanism comprising a housing, a hinged cover for the housing having an opening therein, a door for the opening, a switch within the housing, a latch for the door, an interlock for said latch, an extension on the door, and a plate actuated by the switch and movable across the path of the latch interlock and the said extension for preventing releasing movement of the latch to permit opening movement of the door so long as the switch is in closed position, said plate having recesses which register with said extension and said latch interlock when the switch is in its open position.
2. In combination, a switch box having a

movable cover, a latch for said cover and member in the open position only of the 10 interlock members connected to said cover switch.
and said latch, a switch having a plate member movable therewith, said plate member having a plurality of recesses therein, certain of which register with the cover interlock member in both the open and the closed position of the switch and one of which registers with the latch interlock

In testimony whereof, we have hereunto subscribed our names this 30th day of March, 1921, and this 12th day of April, 1921, respectively.

HAROLD G. BAXTER.
HUBERT K. KRANTZ.
